UNITED STATES PATENT OFFICE.

WILLIAM JAMES LANE AND GEORGE LANE, OF POUGHKEEPSIE, NEW YORK.

MOTOR-VEHICLE.

SPECIFICATION forming part of Letters Patent No. 690,369, dated December 31, 1901.

Application filed March 6, 1901. Serial No. 50,135. (No model.)

To all whom it may concern:

Be it known that we, WILLIAM JAMES LANE and GEORGE LANE, citizens of the United States, residing at Poughkeepsie, county of Dutchess, State of New York, have invented 5 certain new and useful Improvements in Motor-Vehicles, of which the following is a specification.

Our invention relates to motor-vehicles of 10 the type adapted to be operated by steam.

Our invention consists in a construction whereby the feed-water for the boiler is heated 15 by the exhaust-steam from the engine and such portion of such exhaust-steam as is not condensed by the feed-water wholly or partially absorbed by the products of combustion and heated air passing the boiler and before being discharged into the atmosphere.

Our invention also relates to various 20 details of construction, which will be pointed out in the specification and claims.

The object of our invention is to increase 25 the economy of operation of motor-vehicles and also to do away with, as far as possible, the objectionable clouds of steam which commonly follow steam-operated motor-vehicles.

The accompanying drawings will serve to 30 illustrate our invention, in which—

Figure 1 is a longitudinal section taken 35 through the body of a motor-vehicle, as also through the burner and the water-tank, and further shows in elevation a steam-engine and the communicating pipe system between the engine, boiler, and tank. Fig. 2 is a bottom view. Fig. 3 is a transverse section through the vehicle-body looking from the front, also showing the boiler, pipe system, water-gage, &c., in elevation. Fig. 4 is a 40 transverse section through the vehicle-body and water-tank looking from the rear; also showing various pipes in elevation.

In the drawings, 10 indicates the body of a motor-vehicle. The body shown is that of a two-seated vehicle, commonly known as a 45 "surrey." We, however, may use any form of vehicle-body to which our apparatus may be adapted.

Located under the front seat of the vehicle 50 is a vertical-tube boiler 11. Any other type of boiler may be employed. Located under the boiler is a burner 12. Any type of hydrocarbon-burner may be used. The boiler

11 is located within a metallic casing 13, suitably lagged with asbestos or other heat-non-conducting material. The relation of the 55 boiler 11 to the casing is such that there are formed over the top of the boiler a horizontal flue 14 and along the sides of the boiler vertical flues 15. The shape of the casing which incloses the boiler is not material, provided a horizontal flue is provided over the boiler and a vertical flue or flues along the sides of the boiler.

16 indicates the water-tank, located under the rear seat of the vehicle. Entrance is obtained to the water-tank for filling through 65 the removable cover 17.

Situated under the vehicle and between the boiler and the water-tank is a steam-motor device 18. This steam-motor device we prefer to be a two-cylinder engine, although any other form of steam-motor device may be employed.

Connecting the cylinders of the engine to 70 the boiler is a live-steam pipe 19, and in this pipe is a throttle-valve 20, operated through the throttle-lever 21.

Connecting the exhaust of the engine with the interior of the water-tank is a pipe 22. This pipe has its discharge-opening in the top 80 of the water-tank. When steam is discharged through the pipe 22, the water is heated by the steam passing through the pipe and that which is discharged over the water. When the water is cold, the steam is condensed. As 85 the water becomes heated the steam is condensed in smaller quantities.

Connecting the top of the water-tank with the horizontal flue over the boiler is a pipe 23. This pipe is connected in the space occupied 90 by the flue 14 with a transverse pipe 24 and the two branch pipes 25, located in the flue 14 and over the vertical flues 15. The pipes 25 are slotted at 26 underneath, so that steam emitted into these pipes will be discharged in 95 a downward stream at the top of the vertical flues 15.

Instead of placing the slotted pipes 25 at the top of the flues 15 they may be placed further down the flues. We prefer, however, 100 that these pipes should be placed in the top of the flues, as better results are obtained by so doing.

The operation of our improved device so

far as described is as follows: The products of combustion and air drawn through the burner 12 pass through the vertical tubes of the boiler 11 and are discharged in a highly-heated condition into the horizontal flue 14. As this flue is provided with no outlet at the top, the gases are turned downward and into the vertical flues 15. The passage of the body of gases downward is aided by the injector action of the steam discharged from the slots 26 in the pipes 25. As the exhaust-steam and gases pass down the vertical flues 15 the moisture contained in the steam is absorbed in a considerable measure by such gases, it being a well-known fact that these gases will absorb moisture in proportion to their temperature. As a consequence of such action the mingled body of exhaust-steam and gases discharged at the exit-openings of the vertical flues 15 will be nearly if not quite invisible under ordinary temperatures and but very slightly visible when the temperature of the atmosphere is very low or very highly charged with moisture.

Referring again to the drawings, 27 indicates a strainer in the bottom of the water-tank; 28, a steam-pump adapted to be constantly operated by the steam-motor device when it is in motion; 29, a pipe between strainer and inlet of pump; 30 31, inlet and outlet valves from pump; 32, a pipe leading from outlet of pump to boiler; 33, a check-valve at inlet of pipe 32 to boiler. This valve opens inwardly. The pipe 32, as shown in Fig. 3, is carried upward and connected with a valve 34 and then downward, as a pipe 35, back to the water-tank at 36. The operation of this portion of the device will be readily understood. When the steam-motor device is in operation, the pump will be actuated and the water drawn from the tank and discharged through the pipe 32 into the boiler. If the operator of the vehicle finds that sufficient water has been introduced into the boiler, he

opens the valve 34, and as the return-path of pipe 35 to the water-tank offers less resistance than the pressure of the boiler the water will flow around the boiler back to the water-tank.

37 indicates a water-gage on the outside of the vehicle and in a convenient position for observation; 38, try-cocks from the boiler, located between the body of the vehicle and the casing which incloses the boiler.

Having thus described our invention, we claim—

1. In a motor-vehicle, the combination of a boiler, a casing surrounding the boiler, a water-tank, a steam-motor device, an exhaust-pipe leading from the motor device and discharging directly into the water-tank, and an exhaust-pipe leading from the water-tank to the cavity of the casing surrounding the boiler.

2. In a motor-vehicle, the combination of a boiler, a casing surrounding the boiler, a water-tank, a steam-motor device, an exhaust-pipe leading from motor device to water-tank, an exhaust-pipe from water-tank to cavity of casing surrounding the boiler, said pipe having several branches slotted along their lower surface.

3. In a motor-vehicle, the combination of a boiler, a casing surrounding the boiler, a steam-motor device, a feed-pipe for the motor device communicating with the boiler and carried downward and backward within the cavity of the casing, a water-tank, and a pipe connected to the exhaust of the motor device and carried under the body of the vehicle and discharging directly into the water-tank.

In testimony whereof we affix our signatures in presence of two witnesses.

WILLIAM JAMES LANE.
GEORGE LANE.
